UNITED STATES PATENT OFFICE.

MARIE G. SOUTHWORTH, OF FAYETTEVILLE, ARKANSAS.

CORSET.

1,100,156.

Specification of Letters Patent. Patented June 16, 1914.

Application filed June 27, 1913. Serial No. 776,141.

To all whom it may concern:

Be it known that I, MARIE GATES SOUTHWORTH, a citizen of the United States, residing at Fayetteville, in the county of Washington and State of Arkansas, have invented certain new and useful Improvements in Corsets, of which the following is a specification, reference being had to the accompanying drawings.

10 This invention relates to corsets and similar articles of wearing apparel, and has for its primary object to provide a corset of improved construction which will offer the least possible resistance to abdominal and 15 diaphragmatic breathing.

The invention has for another object to provide a corset of improved construction whereby the constricting effect upon the upper part of the thorax as experienced in 20 the use of the ordinary corset is entirely eliminated while that portion of the corset extending downwardly over the lower thorax will readily yield under the pressure of breathing, thus rendering my improved cor- 25 set particularly desirable for use by singers, speakers and the like.

The invention has for a further object the provision of a corset wherein the objectionable upper edge at the top is eliminated, the 30 particular design and construction of the front of the corset and the connections between the same and the back portion thereof materially conducing to the comfort of the wearer.

35 Another object of my invention is to provide a corset of the above character which is light in weight, cool and may be manufactured at comparatively small cost.

With the above and other objects in view 40 as will become apparent as the description proceeds, the invention consists in certain constructions, combinations and arrangements of the parts that I shall hereinafter fully describe and claim.

45 For a full understanding of the invention, reference is to be had to the following description and accompanying drawings, in which—

50 Figures 1 and 2 are front and rear views illustrating my invention in its preferred

embodiment applied to a figure; Figs. 3 and 4 are similar views of a slightly modified construction of the corset. Fig. 5 is a view of the corset shown in Figs. 3 and 4 spread out flat. Fig. 6 is a detail section showing 55 the means for fastening the strap ends to the corset body.

Referring in detail to the drawings and more particularly to Figs. 1 and 2 thereof, 5 designates the side pieces of the corset 60 which are constructed of suitable fabric preferably non-elastic. At their upper ends, these side pieces gradually taper or narrow to a point as indicated at 6, the forward edges thereof curving and gradually merg- 65 ing into the rear longitudinal edge thereof. It will be understood however, that these side pieces may consist of a suitable elastic material, if desired so that they will cling closely to the figure. The longer portions 70 of the side pieces 5 constitute the rear or back edges of the corset and extend upwardly to a point adjacent the shoulder blades of the wearer. These side or body pieces of the corset extend around and down- 75 wardly over the wearer's hips as clearly shown in the drawing. The longer rear edges of the pieces 5 are connected to the longitudinal strips 7 by means of the laces 8. A plurality of elastic straps 9 connect 80 these longitudinal strips 7 and yieldingly hold the same against relative movement under pressure.

The front wall of the corset indicated at 10 includes the bust supporting extensions 85 11, said wall consisting of two separable sections, each of which is gradually attenuated and extended from the extension 11 in the form of a firm, stiff strip 12, which will not be liable to wrinkle. These strips of the 90 front wall sections are provided with suitable fastening members 13 whereby the same may be detachably connected. The outer edges of the front wall sections are connected to the upper and forward edges of 95 the side sections 5 of the corset by means of a plurality of intertwined elastic straps 14. It is to be observed that the upper ends of the side sections 5 are reduced in width or attenuated and above the hips extend rear- 100

wardly upon the back of the wearer. The elastic straps 14 of the corset or garment at each side thereof will thus permit of unrestricted expansion. These straps in conjunction with the elastic back straps 9 serve to normally hold the side pieces 5 closely over the hips of the wearer. It will be noted that the straps 14 do not extend over the upper portion of the thorax so that free muscular expansion and contraction induced by the breathing of the wearer is permitted. These straps extending over the lower portion of the thorax will readily yield or expand under pressure so that they will cause no discomfort.

It will be seen from the above that my improved corset may be easily and quickly applied to and secured upon the body and that by the peculiar construction thereof and the provision of the elastic straps, the numerous disadvantages commonly found in corsets now upon the market have been eliminated.

My improved corset construction permits the free bodily movement of the wearer without discomfort and by the provision of the interwoven elastic straps constituting the major portion of the body of the corset, it will be appreciated that the same is extremely light and cool. The use of the elastic straps 9 on the back of the corset relieves the wearer of the heating effect of the heavy closely woven corset body usually constituting this portion of the ordinary corset.

In Figs. 3, 4 and 5 of the drawings, I have illustrated a slightly modified form of my invention wherein the corset is fastened in the back instead of the front. In this construction, the bust supporting wall 11' is formed in one piece and the lower side edges thereof are connected by the elastic straps 14' to the upper and front edges of the side pieces 5'. The upper ends of these side pieces are connected to the upper edge of the bust supporting wall 11' by means of the shoulder straps 15.

16 designates a plurality of elastic fastening straps secured to the front lower portion of each of the side pieces 5' as indicated at 17. The straps 16 on each of the side pieces are adapted to be extended rearwardly over the hips and detachably fastened to the rear edge of the other side piece by means of suitable fastening members provided for this purpose.

While the advantages above pointed out in connection with my invention are present in this modified construction, the form first described is preferred, in view of the ease and quickness with which the same may be fastened upon the body.

From the foregoing it is believed that the construction and several advantages of the

invention will be clearly and fully understood. It will be obvious that as the same is of extremely simple construction, it may be manufactured at low cost.

My improved corset may be worn with entire comfort and will permit of the unrestricted movement of the body without arranging the same. The corset will also at all times retain its proper adjusted position in close engagement with the body of the wearer.

It will be observed that by means of my improved corset construction, the usual sharp upper edge is eliminated. In corsets of the general construction, when the wearer assumes various postures, this sharp edge of the corset is outlined beneath the waist and thus greatly detracting from the appearance.

While I have shown and described the preferred construction of my invention, it will be obvious that the same is susceptible of considerable modification and I therefore reserve the right to resort to all such legitimate changes as may be fairly embodied within the scope of the invention, as claimed.

Having thus described the invention, what is claimed is:

1. A corset comprising two similar side pieces, each having its upper portion gradually reduced in width and extending rearwardly over the hips of the wearer when the corset is applied, yielding means between said sections to restrict relative movement of said sections at their rear edges, a bust supporting wall, and intertwined elastic straps connecting said wall at its edges to the forward edges of said side pieces, said intertwined straps extending substantially the entire length of said side pieces and over the abdomen and upper side portions of the wearer's body.

2. A corset comprising two similar side pieces each having an attenuated upper portion located rearwardly and above the hips of the wearer when the corset is applied, means yieldably connecting said side pieces to retain the same in close engagement with the body of the wearer, a bust supporting wall consisting of two sections, means for detachably connecting said sections, and intertwined elastic straps connecting each of said sections to the forward edge of one of the side pieces.

3. A corset comprising two similar side pieces having their forward edges curved to extend above and rearwardly of the wearer's hips, a bust supporting wall consisting of two sections extending above the upper ends of said side pieces, means for detachably connecting said bust wall sections, each of said sections being provided with a comparatively narrow depending

strip, said strips being also adapted for
detachable connection to each other, elastic
straps connecting the rear edges of said
side pieces, and intertwined elastic straps
5 connecting each of the bust wall sections
and the depending strip thereof to the for-
ward edge of one of said side pieces.

In testimony whereof I hereunto affix my
signature in the presence of two witnesses.

MARIE G. SOUTHWORTH.
